Primary Examiner — Karen E Eldridge Powers(74) *Attorney, Agent, or Firm* — Knobbe Martens Olson & Bear LLP(57) **CLAIM**

The ornamental design for a personal care device with camera, as shown and described.

DESCRIPTION

FIG. 1 is a bottom, front perspective view of an embodiment of a personal care device with camera embodying my design;

FIG. 2 is a top, rear perspective view of the embodiment;

FIG. 3 is a front view of the embodiment;

FIG. 4 is a rear view of the embodiment;

FIG. 5 is a left side view of the embodiment;

FIG. 6 is a right side view of the embodiment;

FIG. 7 is a top view of the embodiment; and,

FIG. 8 is a bottom view of the embodiment.

The broken lines shown in the figures represent portions of the personal care device with camera that form no part of the claimed design.
